STEAM HEATING SYSTEM

Miril E. Whitenack, New York, N. Y., assignor to
 Whitenack Corporation, Chicago, Ill., a corpora-
 tion of Illinois

Application May 24, 1937, Serial No. 144,357

11 Claims. (Cl. 237—9)

This invention relates to steam heating systems, such, for example, as are used for heating buildings and is concerned more particularly with a novel heating system which includes heat radiating units receiving steam from a source of supply, and a control mechanism for regulating the supply of steam to these units. This application is a continuation in part of my copending applications Serial No. 41,503, filed September 10, 1935, and Serial No. 118,092, filed December 29, 1936.

In heating systems as now commonly installed, the control mechanism generally is located at a point of heat radiation, or at a point out-of-doors, 15 and is responsive only to changes in conditions at those points. In any ordinary building, it is difficult, if not impossible, to place the control mechanism at a point which will enable it to regulate the temperature satisfactorily throughout the building, and with such systems, certain rooms are likely to be overheated while others are not heated enough. Such systems are wasteful of steam and do not produce the desired result of effecting close regulation of temperatures.

25 In the system of the present invention, the control mechanism responds to changes in the system at or near the point of supply of the steam. The control mechanism is made responsive to the sum of the static pressure prevailing 30 in the system and the velocity pressure of steam flowing in the system near the point of admission to the system, and operates automatically to correlate the rate at which steam is supplied to the radiating units with the rate at which it is consumed therein. The control mechanism of the system is extremely prompt and sensitive in its action and acts to vary the amount of steam supplied to correspond closely to changes in demand, with the result that over-running of the supply 40 with incident waste of heat is eliminated and substantially constant temperatures are maintained with great economy.

It is advantageous to operate steam heating systems at subatmospheric pressures to secure 45 the greater heating efficiency that accompanies the use of low steam pressures. In operating heretofore known heating systems at subatmospheric pressures, it has been necessary to provide traps, check valves, and similar devices on the 50 outlet side of the radiating units to prevent the escape and consequent waste of uncondensed steam. The present steam heating system preferably is operated at subatmospheric pressures, and owing to the accuracy with which the control mechanism of the system regulates the flow of

steam, traps or similar devices on the outlet side of the radiating units may be dispensed with. A substantially unobstructed, trapless conduit provides for the withdrawal of condensate from the radiating units. 5

In operating the heating system of the invention, particularly at a subatmospheric pressure, a partial pressure of air or other non-condensable gas is maintained therein. A partial pressure of such a gas in the system reduces the partial pressure due to steam and results in improved heating economies. More important, however, is the fact that the presence of air in the system, especially when the total pressure in the system is below that of the atmosphere, greatly improves the efficiency with which the control mechanism operates. In a system operating at subatmospheric pressures and from which air has been excluded, it is not possible to secure the same close control over steam admission and accompanying heating 20 economies that are obtained when a partial pressure of air is present. 15

For a better understanding of the invention, reference is made to the accompanying drawing, in which

Fig. 1 is a diagrammatic representation of a steam heating system in accordance with the invention; and

Fig. 2 is a diagrammatic representation of a modified arrangement of apparatus for regulating the pressure in the system. 30

In the steam heating system shown in the drawing, steam from a source such as a high-pressure steam main 10 is admitted to a header or distributing conduit 11 through a valve 12. 35 Branch conduits 13 connected to the header or distributing conduit 11 conduct steam to radiators 14 suitably located in the various rooms of a building to be heated and into the inlet side of which steam is admitted through suitable inlet pipes 15, shown as connected to the bottom of the radiators, as the radiators are built for bottom feed. A return line 16 is connected with the outlet side of the radiators 14 by means of suitable outlet pipes 17 and with means for regulating the 40 pressure in the system. Advantageously the pressure in the system is maintained below atmospheric pressure, and in consequence the pressure-regulating means ordinarily takes the form of a vacuum pump 18 set to maintain a chosen 45 subatmospheric pressure in the radiating means and throughout the system. 50

Suitable control mechanism is provided to govern operation of the valve 12 and thereby to regulate admission of steam to the system. The con- 55

trol mechanism comprises a pressure-sensitive element, preferably in the form of an expandible bellows 20, with which a tubular member 21 is connected. The tubular member 21 extends into the interior of the conduit or header 11 where it is positioned in the path of steam flowing therethrough. The lower end of the tubular member 21 is suitably configured to enable it to transmit to the pressure-sensitive bellows 20 the sum of the static pressure prevailing in the header and the velocity pressure of steam flowing therethrough. A suitable configuration for this purpose is provided by forming the lower end surface of the tubular member 21 at an acute angle to the axis of the member. A substantially lateral opening thereby is provided at the lower end of the tubular element, and this substantially lateral opening is faced substantially into the path of the flowing steam.

20 A rocker arm 22 mounted to rock about a pivot point 23 is pivotally connected at one end to the expandible bellows 20. A spring 24 bears against the other end of the rocker arm 22. The spring is mounted in such manner that the force it exerts on the rocker arm may be adjusted exactly to counterbalance the pressure exerted on the bellows 20 when conditions in the header are at the values it is desired to maintain. If the pressure maintained in the header 11 is above atmospheric, the spring 24 is under tension, but if, as is preferred, the pressure in the header 11 is below that of the atmosphere, the spring is under compression. In either case, the force exerted by the spring on the rocker arm 22 is adjusted to counteract the force exerted on the rocker arm by the bellows when desired conditions prevail in the header 11.

40 A contact arm 25 is secured to the rocker arm 23 adjacent the pivoted mounting 23 thereof. Contact points 26 and 27 are arranged on either side of the contact arm 25 adjacent its lower end. The contact points 26 and 27 are spaced from each other and from the contact arm so that the contact arm may move back and forth to 45 make contact with either contact point or to assume a neutral position midway between them.

50 The above-described control mechanism governs operation of the valve 12 through which steam is admitted to the header 11 through the agency of an electrically operated pilot valve assembly. The pilot valve assembly comprises a housing 30 divided into a lower compartment 31 and an upper compartment 32 by a partition 33. An opening 34 extending through the partition 33 provides for communication between the lower compartment 31 and the upper compartment 32, and a pilot valve 35 is arranged to seat in this opening. A valve stem 36 is connected at one end to the pilot valve 35 and through suitable gearing (not shown) at the other end to a pair of electric motors 37 and 38. One of the motors 37 (hereinafter referred to as the opening motor) operates on the valve stem 36 to raise the pilot valve 35 from its seat in the opening 34, and the other motor 38 (referred to hereinafter as the closing motor) actuates the valve stem 36 to move the pilot valve toward its seat in the opening 34.

70 A steam tube 39 serves to admit steam under pressure from the main 10 to the lower compartment 31 of the pilot valve assembly. A bleed-off tube 40 provides means of communication between the upper compartment 32 of the pilot valve assembly and the header 11 to permit the escape of steam passing from the lower com-

partment 31 through the opening 34 into the upper compartment.

75 The main valve 12, operation of which is controlled by the pilot valve assembly described above, is a diaphragm valve of conventional construction comprising a steam chamber 42 defined by a rigid domed upper wall 43 and a flexible diaphragm 44. The domed upper wall 43 and the diaphragm 44 are mounted on suitable supporting members 45 connected to the casing 10 of the valve 12. The stem 46 of the main valve 12 is connected to the flexible diaphragm 44 adjacent the center thereof. A tube 47 connects the steam chamber 42 with the lower compartment 31 of the pilot valve assembly. 15

When the pilot valve 35 is seated in the opening 34, steam under pressure from the main 10 passes through the steam tube 39 to the lower compartment 31 of the pilot valve assembly and thence through the tube 47 to the steam chamber 42. 20

Substantially the full pressure of the steam in the main 10 thus is exerted on the diaphragm 44, and in consequence the stem 46 of the valve 12 is pressed down with sufficient force to hold the valve 12 closed against the pressure of the steam from the main. If the pilot valve 35 is opened slightly, steam is allowed to escape at a low rate from the lower compartment 31 of the pilot valve assembly into the upper compartment 32 and thence through the bleed-off tube 40 into the header 11. As a result the pressure in the lower compartment 31 and in the steam chamber 42 is diminished somewhat and the main valve is forced open slightly by the pressure of the steam in the main. Further opening of the pilot valve 35 results in further diminution of the pressure in the lower compartment 31 and in the steam chamber 42 and in further opening of the main valve 12. The extent by which the pilot valve 35 is opened thus controls 25 the extent by which the main valve 12 is opened and the rate at which steam is admitted from the main 10 to the header 11. 30

35 The contact arm 25 and the contact points 26 and 27 are connected through any suitable quick-acting electric control 50 with the opening and closing motors 37 and 38 of the pilot valve assembly. A number of suitable electric control circuits are available, but a circuit such as described in my copending application Serial No. 109,559, filed November 6, 1936, is preferred. It will suffice for a complete understanding of the present invention to point out that the control circuit is such that when the contact arm 25 is moved close to or into contact with one of the contact points 26, the opening motor 37 is energized and the pilot valve 35 is opened, and when the contact arm is moved close to or into contact with the other contact point 27, the closing motor 38 is energized and the pilot valve is 40 closed. 45

50 The control mechanism functions closely to correlate the rate of admission of steam to the system through the main valve 12 with the rate of consumption of steam in the system. Whenever there is a demand for steam in excess of the rate at which steam is at that moment being admitted, there is a slight decrease in the pressure exerted within the bellows 20, and the bellows collapses sufficiently to move the contact 55 arm 25, through the rocker arm 22, toward the contact point 26. The opening motor 37 thereupon is energized and the pilot valve 35 opens, and the main valve 12, in response to the opening of the pilot valve, also opens and admits steam 60 65

to the system at an increased rate. On the other hand, if the demand for steam decreases at any moment to below the rate of admission of steam, the pressure within the bellows increases 5 and the contact arm is moved toward the contact point 27 through which the closing motor 38 is energized. The pilot valve thereupon is closed and the main valve 12 closes correspondingly, thus decreasing the rate of admission of 10 steam to the system.

The control mechanism closely correlates the rate of admission of steam to the system with the rate of demand for steam. Since the control mechanism is responsive to the sum of the 15 static pressure in the system and the velocity pressure of steam passing the tubular member 21, it prevents the admission of more steam than is necessary to the system, but at all times admits sufficient steam to meet, within the limits imposed by the capacity of the system, the demand 20 for steam.

In operation of the system, it is preferable to maintain the pressure therein at some constant value below that of the atmosphere, say at some 25 value between about 500 and 380 millimeters absolute (corresponding to between about 10' and 15' of mercury vacuum), thereby to secure the benefit of heat economies possible with low pressure steam. This pressure may be maintained 30 by a piston type vacuum pump 18 set to maintain the pressure in the radiating units at the chosen value. The piston vacuum pump also serves to withdraw condensate passing from the radiating units through the outlet pipes 17 and 35 the return line 16 and to discharge it through a conduit 51 to waste.

A modified arrangement of pumps for regulating the pressure in the radiating units is shown in Fig. 2, in which the return line 16 from the radiating units 14 terminates in a sump 52. A 40 centrifugal type vacuum pump 53 connected with the sump 52 near the bottom thereof serves to withdraw condensate collecting in the sump and expel it to waste through a conduit 54. A second 45 centrifugal type vacuum pump 55, advantageously on the same shaft as the pump 53, is connected to the return line 16 at a point above the sump. This second vacuum pump 55, which is set to maintain a proper predetermined pressure in the radiating units, serves to withdraw 50 and expel through a conduit 56 such non-condensable gases as enter the system by leakage or with incoming steam.

In operating the heating system of the invention, particularly at subatmospheric pressures, it 55 is highly desirable to maintain a partial pressure of air or other non-condensable gas therein. If the total pressure in the system is made up in part by the pressure of a non-condensable gas such as air, the part of the total pressure due to steam is correspondingly reduced; in consequence the presence of air aids in securing the benefits of economy accompanying the use of low steam pressure. The presence of air or other 60 non-condensable gas also has an important bearing on the efficiency with which the control mechanism regulates admission of steam to the system, particularly when the total pressure in the system is below that of the atmosphere. In 65 a system operating at a subatmospheric pressure from which air has been excluded, it has been found that the same close control over the admission of steam and the attendant heating economies obtained when air is present in the 70 system are not secured. The exact proportion 75

of air or other non-condensable gas to steam varies from time to time and from system to system, but in general it is substantial. In some instances the partial pressure of air in the system may amount to 75% or more of the total 5 pressure, and in general amounts to between about 25% and 75% of the total pressure.

A feature of the heating system of the invention is the provision of a substantially unobstructed conduit for the withdrawal of condensate and communicating with the interior of the radiating units and with the vacuum pump regulating the pressure in the system. It has been customary heretofore to provide traps, check valves, or other obstructions in the outlet pipe 10 through which condensate is removed from the radiating units in order to prevent the escape of uncondensed steam and consequent waste of heat. Traps or the like have been particularly necessary in heating systems operating at sub- 15 atmospheric pressures because of the suction of the vacuum pump tending to pull steam from the system. Traps and the like are objectionable adjuncts to any heating system because of the ease with which they become clogged with 20 rust, grit, or other solid matter that prevents the escape of condensate and thereby seriously interferes with operation of the radiating units. Moreover, traps provide a material item in the initial cost of any heating system having a con- 25 siderable number of radiating units, and their upkeep adds considerably to maintenance costs of the system.

In the system of the invention, the admission 30 of steam is so closely correlated with the demand imposed on the system that traps in the outlet 35 from the radiating units are unnecessary. The outlet pipes 17 and the return line 16 afford an unobstructed passage of adequate size for the withdrawal of condensate from the radiating 40 units.

In consequence of the precision with which the admission of steam to the heating system of the invention is controlled, provision of hand 45 valves on the inlet pipes 15 to the radiating means 14 is made unnecessary, and no such valves are shown in the drawing. The presence of such valves, however, is not objectionable, and in installations where it may be desirable to shut off some radiating units while operating others, 50 the provision of hand valves in the inlet pipes 15 may be advantageous.

It is understood that the specific description of the invention given above is by way of example and that modifications can be made in the 55 apparatus without departing from the invention. For example, the particular form of pilot valve described is only one of a number of devices available to the art as the agency through which the valve governing admission of steam to the 60 system is controlled. It is also understood that in referring to the control mechanism as being responsive to the velocity pressure of steam flowing in the system, the word "steam" is used in this connection generically to mean other gases 65 such as air as well as steam.

The heating system of the invention operates 70 efficiently and economically. Even in large buildings, the system of the invention achieves excellent circulation of steam through all radiating units. The close control over admission of steam to the system afforded by the control mechanism substantially avoids over-supply of steam and consequent waste of heat while at all times admitting enough steam to meet the demand im- 75

posed on the system. Elimination of parts such as traps, necessary for successful operation of heretofore known systems, greatly reduces both the first cost and upkeep of the system of the invention. In actual operation of heating systems according to the invention, substantial economies in operating and maintenance costs, as compared with corresponding costs of systems supplanted by the system of the invention, have been achieved.

I claim:

1. A steam heating system comprising a source of steam, heat radiating means, a conduit leading from the source to the radiating means, mechanism responsive to the sum of the static pressure prevailing in the conduit and the velocity pressure of steam flowing in the conduit, means for varying the admission of steam to the conduit, and means actuated by said pressure-responsive mechanism for actuating the steam-admission varying means to increase the rate of steam admission to the conduit upon a decrease of the static pressure of the steam in the conduit and also upon a decrease of the velocity pressure of the steam therein, and to decrease the rate of steam admission upon an increase of the static pressure of the steam in the conduit and also upon an increase of the velocity pressure of the steam therein, whereby the rate at which steam is admitted to the conduit is correlated with the rate at which it is consumed in the radiating means.

2. A steam heating system comprising a source of steam, heat radiating means, a conduit leading from the source to the radiating means, a valve through which steam is admitted from the source to the conduit, mechanism responsive to the sum of the static pressure prevailing in the conduit and the velocity pressure of the steam flowing in the conduit and including a tubular element extending into the interior of the conduit, and means actuated by said pressure-responsive mechanism to open said valve and increase the rate of steam admission to the conduit upon a decrease of the static pressure of the steam in the conduit and also upon a decrease of the velocity pressure of the steam therein, and to close said valve to decrease the rate of steam admission upon an increase of the static pressure of the steam in the conduit and also upon an increase of the velocity pressure of the steam therein, whereby the rate at which steam is admitted to the conduit is correlated with the rate at which it is consumed in the radiating means.

3. A steam heating system comprising a source of steam, heat radiating means, a conduit leading from the source to the radiating means, mechanism responsive to the sum of the static pressure prevailing in the conduit and the velocity pressure of steam flowing in the conduit, means for varying the admission of steam to the conduit, means actuated by said pressure-responsive mechanism for actuating the steam-admission varying means to increase the rate of steam admission to the conduit upon a decrease of the static pressure of the steam in the conduit and also upon a decrease of the velocity pressure of the steam therein, and to decrease the rate of steam admission upon an increase of the static pressure of the steam in the conduit and also upon an increase of the velocity pressure of the steam therein, whereby the rate at which steam is admitted to the conduit is correlated with the rate at which it is consumed in the radiating means, pressure regulating means for maintaining a predetermined pressure in the radiating means, and a substantially unobstructed conduit communicating with the interior of the radiating means on the outlet side thereof and with the pressure regulating means for the withdrawal of condensate from the radiating means.

4. A steam heating system comprising a source of steam, heating radiating means, a conduit leading from the source to the radiating means, a valve through which steam is admitted from the source to the conduit, mechanism responsive to the sum of the static pressure prevailing in the conduit and the velocity pressure of steam flowing in the conduit and including an element extending into the interior of the conduit, means actuated by said pressure-responsive mechanism for opening said valve to increase the rate of steam admission to the conduit upon a decrease of the static pressure of the steam in the conduit and also upon a decrease of the velocity pressure of the steam therein, and to close said valve and decrease the rate of steam admission upon an increase of the static pressure of the steam in the conduit and also upon an increase of the velocity pressure of the steam therein, whereby the rate at which steam is admitted to the conduit is correlated with the rate at which it is consumed in the radiating means, pressure regulating means for maintaining a predetermined pressure in the radiating means and a substantially unobstructed conduit communicating with the interior of the radiating means on the outlet side thereof and with the pressure regulating means for the withdrawal of condensate from the radiating means.

5. A steam heating system comprising a source of steam, heat radiating means, a conduit leading from the source to the radiating means, a valve for controlling the admission of steam to the conduit, mechanism responsive to the sum of the static pressure prevailing in the conduit and the velocity pressure of steam flowing in the conduit and including a tubular element extending into the conduit having an opening facing substantially into the path of flow of steam in the conduit, means actuated by said pressure-responsive mechanism for opening said valve to increase the rate of steam admission to the conduit upon a decrease of the static pressure of the steam in the conduit and also upon a decrease of the velocity pressure of the steam therein, whereby the rate at which steam is admitted to the conduit is correlated with the rate at which it is consumed in the radiating means, pressure regulating means for maintaining a predetermined pressure in the radiating means, and a substantially unobstructed conduit communicating with the interior of the radiating means on the outlet side thereof and with the pressure regulating means for the withdrawal of condensate from the radiating means.

6. A steam heating system comprising a source of steam, heat radiating means, a conduit leading from the source to the inlet side of the radiating means, mechanism responsive to the sum of the static pressure prevailing in the conduit and the velocity pressure of steam flowing in the conduit, means for varying the admission of steam to the conduit, means actuated by said pressure-responsive mechanism and actuating the steam admission varying means to increase the rate of steam admission to the conduit upon a decrease of the static pressure of the steam in the conduit and also upon a decrease of the velocity pressure of the steam therein, and to decrease the rate of steam admission upon an increase of the static pressure of the steam in the conduit and also upon an increase of the velocity pressure of the steam therein, whereby the rate at which steam is admitted to the conduit is correlated with the rate at which it is consumed in the radiating means, pressure regulating means for maintaining a predetermined pressure in the radiating means, and a substantially unobstructed conduit communicating with the interior of the radiating means on the outlet side thereof and with the pressure regulating means for the withdrawal of condensate from the radiating means.

7. A steam heating system comprising a source of steam, heat radiating means, a conduit leading from the source to the inlet side of the radiating means, mechanism responsive to the sum of the static pressure prevailing in the conduit and the velocity pressure of steam flowing in the conduit, means for varying the admission of steam to the conduit, means actuated by said pressure-responsive mechanism and actuating the steam admission varying means to increase the rate of steam admission to the conduit upon a decrease of the static pressure of the steam in the conduit and also upon a decrease of the velocity pressure of the steam therein, and to decrease the rate of steam admission upon an increase of the static pressure of the steam in the conduit and also upon an increase of the velocity pressure of the steam therein, whereby the rate at which steam is admitted to the conduit is correlated with the rate at which it is consumed in the radiating means, pressure regulating means for maintaining a predetermined pressure in the radiating means, and a substantially unobstructed conduit communicating with the interior of the radiating means on the outlet side thereof and with the pressure regulating means for the withdrawal of condensate from the radiating means.

MIRI E. WITTENACK.
